UNITED STATES PATENT OFFICE.

JOSEPH O. FISHER, OF THE UNITED STATES NAVY.

APPARATUS FOR MUFFLING SOUNDS.

1,341,976.

Specification of Letters Patent.

Patented June 1, 1920.

Application filed January 23, 1918. Serial No. 213,362.

To all whom it may concern:

Be it known that I, JOSEPH O. FISHER, a commander in the United States Navy and a citizen of the United States, residing at 5 Washington, in the District of Columbia, have invented certain new and useful Improvements in Apparatus for Muffling Sounds; and I do hereby declare the following to be a full, clear, and exact description of the invention, such as will enable others skilled in the art to which it appertains to make and use the same.

This invention relates to an apparatus for muffling sounds and has for its object to 15 provide a means which will be more efficient in use than those heretofore proposed.

With this and other objects in view the invention consists in the novel combinations of parts constituting the apparatus, all as 20 will be more fully hereinafter disclosed and particularly pointed out in the claims.

Referring to the accompanying drawings forming a part of this specification in which like numerals designate like parts in all the 25 views:—

Figure 1 is a side elevational view partly in section of a muffler made in accordance with this invention;

Fig. 2 is a view of a somewhat modified 30 form of rotator or helically disposed element removed from the casing;

Fig. 3 is an end view of the parts shown in Fig. 2;

Fig. 4 is a sectional view of a casing 35 partly broken away with a still further modified form of rotator located therein;

Fig. 5 is a cross sectional view taken on the line 5—5 of Fig. 6, showing another modified form of helical element or rotator;

Fig. 6 is a sectional view taken on the 40 line 6—6 of Fig. 5; and

Fig. 7 is a sectional view of a still further modified form of rotator;

As is well known, sounds caused by exhaust gases from engines and other apparatus are due to the intermittent discharge of said gases along some line of translation into the atmosphere, and the purpose of this invention, more specifically stated, is to convert the motion of translation possessed by said gases into motion of rotation, and thus destroy their power of causing said sounds, as will be clear from the construction now to be disclosed.

1 may represent any suitable discharge or

exhaust pipe for the gases from an engine or other apparatus, 2 a connection between said pipe and the muffler casing 3, 4 a chamber in the discharge end of said casing, 5 any suitable discharge pipe joined to the 60 chamber 4 and 6 any suitable cooling means.

The gases causing the sounds to be muffled are received into a chamber 8 with which the inlet end of the casing 3 is provided, in the form of pulsations directed along the axis of 65 said casing 3. From the chamber 8 the gases impinge on the surface 10 of the rotator or helical element 9, and they follow the convolutions of said element 9 until they reach the chamber 4. In order that the said gases, 70 after striking the surface 10, may not pass along the axis of the chamber 3 without receiving a rotational movement, I cause the blade of the rotator 9 to have a depth 11 which is sufficient to at least reach the center line of said casing, and it may be, if desired, extended beyond said center line. It thus results that the gases are compelled to traverse and cross the helical chamber 75 formed by the convolutions of the rotator 9, 80 and the casing 3 without motion in a straight line along the axis of said casing 3 until they have rotated through an angle of say 270° or 360°, or several complete revolutions.

After having rotated through some predetermined angle of a considerable dimension, I then permit the said gases to gradually escape in a straight line along the axis of the casing 3, by gradually cutting away 85 the inner edge 17 of said helical element 9. This said cutting away of this said edge may begin at or about the point 18, illustrated in Fig. 2, or at about the point 31, illustrated in Fig. 4. The cutting away of 90 the said inner edge 17 of the helical element 9 produces a tapered orifice axially disposed with reference to the casing 3 which orifice is lettered 12 in Fig. 4, and 18 in Fig. 2. Further, in order to more effectually absorb 95 the energy of translation of said gases or rather to more effectually convert the said energy into rotational energy, I preferably decrease the pitch of the rotator 9 beginning at or about the point 125 in Fig. 4, but 100 of course, it is understood this decrease of the pitch may begin at any other points along the axis of the rotator. The decreasing 105 of the pitch of the screw increases the length of the path of the gases in the heli- 110

cal chamber formed between the helical surface and the casing 3 and it is found to have in practice a beneficial effect in decreasing the sounds which would otherwise be emitted by said gases. That is to say, by compressing the pitch of the rotator 9 in the manner described, the pulsating energy of the gases is destroyed at an increasing or accelerated rate, and converted into rotational energy, by reason of the increasing obstruction offered by said compressed pitch. This would not be the case were the action reversed, and the pulsating gases allowed to traverse an expanding rotator, for the necessary obstruction to a pulsating action would, in that case, be taken away. Again, as this said obstruction, due to the compressed pitch of the rotator, begins to destroy said pulsating action of the gases, the cutaway portion 17 of said rotator permits the rotating gases to escape out of the apparatus in the form of an expanding cone, so that a maximum of noise is suppressed, or prevented. Put into still other words, the gases having been thus given a substantial rotation around the axis of the chamber 3 without any opportunity at all to pulsate along the axis of said casing, the energy of motion possessed by the entering gases will be found to have been very largely, if not entirely converted into centrifugal energy, although there will be a greater or less pulsating of the said gases along the direction of their helical path. The centrifugal force of the said rotating gases causes the same to continue their pulsating action at a maximum distance from and around, rather than along the axis of the chamber, and therefore, they do not create the noise which would accompany said escape if they pulsated in the direction of the said axis.

By the time the gases have reached the chamber 4, illustrated in dotted lines in Fig. 1, the inner edge 17 of the rotator has been so much cut away that substantially all the gases will rotate around the axis of said chamber 3, and by their own pressure, will pass out of said chamber into the atmosphere or into a discharge pipe such as 5, through an orifice of less diameter than the chamber and concentric with the axis of the rotating gases, as the case may be. When so discharged, it is found in practice that very little, if any noise accompanies said gases.

The helix or rotator 9 is conveniently supported at each end by the spider like members 20 and 21, which spiders are conveniently held together as by the strips 22, and these supports may be inserted as a whole in the casing 3.

In the slightly modified form of rotator illustrated in Figs. 2 and 3, I have provided

a foraminous covering, which fits the interior of its casing such as 3, and as it exerts a cushioning action and offers considerable resistance to the propagation of any sound waves produced by the entering gases, it aids in absorbing any sound waves that may exist in said gases, and thereby aid in still further reducing the sounds that would otherwise be produced. Said foraminous covering may be made of any suitable material, but one or more layers of wire cloth is preferred. In the still further modified form of the invention shown in Fig. 4, the rotator is made up of separate sections 25 which are joined as at 26 to form the helix, and a similar foraminous covering 76 is also employed. The function of the covering 76 is substantially the same as that of the covering 75 and need not be repeated.

This said construction shown in Fig. 4 avoids the difficulty of properly shaping a single piece such as that lettered 9 in Fig. 2, and it renders it comparatively easy to locate the inner edge 17 of the individual sections 25 either directly in the axis of casing 3, or somewhat to one side of said axis, as may be desired by the manufacturer. It is also comparatively easy to impart to a helix produced from sections 25 any desired decreased twist, as will be clear from the points lettered 27, 28, 29 and 30 in Fig. 4. It is also easier in the manufacture of these helices to so cut away the inner edges 17 of said sections 27 to 30 as to regulate to a nicety the shape and dimensions of the tapered discharge orifice 12 as is indicated by the dotted lines in Fig. 4.

In the still further modified form of rotator, shown in Fig. 5, the gases may enter the opening 35 of the pipe 34, while still pulsating in a straight line whereupon they will acquire a greater and greater angular or spiral motion in the same plane, so that this said angular motion coupled with its increase in angularity will serve to convert with quickness and efficiency the energy of motion into centrifugal energy after the gases have thus traveled in the direction of the arrows shown in Fig. 5, and have reached say the point 36 in said figure. The outlet 37 is given a helical form and the said gases are discharged into the chamber 38 tangentially to the circumference of the same, and the said gases continue to rotate, until their own pressure finally forces them to emerge through a discharge opening 39, similar in all respects to the opening 57 in Fig. 7, while they are still rotating. Here again, although the gases may possess a pulsating action along their line of motion, while rotating about an axis, yet at the same time, in practice on emergence through opening 57 they are found not to be accompanied by any substantial noises.

Coming now to the still further modified form of the invention shown in Fig. 7, the pulsating gases may be received in the inlet 50 of the pipe 49 whereupon they are given a helical motion by the convolutions 51, 52, and 53, the said gases being finally discharged from the end 55 of said convolutions into the cylindrical chamber 54, around the circumference of which they likewise continue to rotate until finally their pressure will force them to pass through an opening 57 of less diameter than the path of rotation, and into the atmosphere, while they are still rotating around their axis of rotation.

Here again, it will be observed that the energy of motion of said gases has been converted into centrifugal energy of rotation, but this last mentioned motion, although still subject to pulsations, is found in practice to be incapable of causing the sounds when discharged to the atmosphere as above described.

A foraminous covering member such as 75 or 76 is employed as a lining for the gas passages in Figs. 5, 6 and 7, but it is not deemed necessary to illustrate it here.

It will now be clear that in all the forms of the invention:

30 First, that I start with an intermittent, or pulsating stream of gases having a motion in a given direction; that I convert a large part or substantially all the energy of motion possessed by said gases into centrifugal energy while at the same time, I discharge the said gases in a rotating stream along the axis of rotation, and therefore, in a form which is not capable of producing the sounds which otherwise would occur.

40 Second, it will be observed that I line the gas passages with a foraminous covering which absorbs any sound waves and prevents the propagation of said sound waves along the gas passages.

45 Since the gases enter the connection 2 in the form of a stream pulsating in a straight line, and since they are immediately, for a portion of their travel, forced by the helical members 9 or 25, to rotate around the longitudinal axis of the casing 3, it is evident that some of their original energy will be used up in acquiring this rotary motion. Therefore, said gases cannot after leaving said casing 3 pulsate in a straight line as violently as they could before entering the connection 2. If the rotational energy thus created at the expense of the pulsating energy is made relatively large, it is obvious that the pulsations in a straight path will

55 be relatively small, and that the noise of the muffler will be correspondingly reduced. This desirable result is enhanced by gradually opening a straight line path of escape for the rotating gases, as by cutting away the inner edges of the helices 9 or 25, and at

the same time decreasing the pitch of said helices to partially obstruct any straight line pulsations that may still persist in the outer boundaries of said rotating gases.

It is therefore an especially important feature of the invention that my discharge orifices such as 12, 18, 39 and 57 are in a prolongation of the axis of rotation, for, while the gases were originally subject to pulsations due to wide variations in velocity 75 their centrifugal force absorbs the energy of the gases of the highest velocity, and said orifices being free from all obstructions in the paths of rotation, the gases of lowest velocity are gradually forced by their own 80 pressure into said orifices, and out of the same without disturbing their continuous rotation. Accordingly, the tendency of said gases to take up an intermittent movement in the direction of the axis of the rotator is reduced to a minimum. 85

It is an equally important feature of my invention that the gas passages are lined with a foraminous roughened, or other sound absorbing material, which prevents 90 the propagation of the sounds produced by the gases entering the muffler.

It is obvious that those skilled in the art may vary the details of the process as well as the construction and arrangement of 95 parts constituting the apparatus without departing from the spirit of the invention and therefore, I do not wish to be limited to the above disclosure except as may be required by the claims. 100

What I claim is:

1. The process of muffling sounds due to pulsating, intermittent or periodic discharges of gases into the atmosphere which consists in imparting to said gases a rotary 105 motion in a chamber to convert a part of their energy of motion into centrifugal energy; partially obstructing the pulsations of said gases while rotating the same to convert another portion of their energy into centrifugal energy and discharging said gases in an unobstructed expanding rotating stream from said chamber, open to the atmosphere, substantially as described. 110

2. An apparatus for muffling sounds comprising a chamber provided with a rotator adapted to impart to gases having a pulsating or intermittent motion a motion of an accelerated rotation, and having a cone shaped orifice of less diameter than said 120 path of rotation freely opening into the chamber and adapted to discharge said gases therefrom in an unobstructed rotating stream, substantially as described.

3. In an apparatus for muffling sounds the 125 combination of a casing provided with an inlet and an outlet; and a helical member having a varying pitch located in said casing; said member near said outlet being cut away to provide an unobstructed discharge 130

opening from said chamber to said outlet, substantially as described.

4. In an apparatus for muffling sounds the combination of a casing provided with 5 receiving and discharge chambers, and with an inlet and an outlet respectively for said chambers; and a helically disposed member located in said casing between said chambers and cut away near its outlet end to provide 10 an unobstructed passage to said discharge chamber, substantially as described.

5. In an apparatus for muffling sounds the combination of a casing; an inlet for 15 said casing; a receiving chamber in said casing into which said inlet leads; an outlet for said casing; a discharge chamber in said casing from which said outlet leads; and a helically disposed member having a decreasing pitch located between said chambers to 20 form a continuous helical chamber in said casing, the inner edge of said member being cut away near said discharge chamber to form an unobstructed connection between said helical and discharge chambers, sub- 25 stantially as described.

6. In an apparatus for muffling sounds the combination of a casing; an inlet for 30 said casing; a receiving chamber in said casing into which said inlet leads; an outlet for said casing; a discharge chamber in said casing from which said outlet leads; and a helically disposed member having a decreasing pitch located between said chambers to 35 form a continuous helical chamber in said casing, the inner edge of said member for a portion of its length extending radially as far as the axis of said chamber, and for the rest of its length being gradually cut

away to form an unobstructed tapering connection between said helical and discharge 40 chambers, substantially as described.

7. The process of muffling sounds due to intermittent discharges of gases into the atmosphere, which consists in converting the energy of motion of said intermittent dis- 45 charges into an accelerated rotary motion while subjecting said gases to the muffling action of a foraminous substance and discharging said gases in an unobstructed rotating and, expanding stream into the air, 50 substantially as described.

8. An apparatus for muffling sounds comprising a chamber having a rotator adapted to impart to gases having a pulsating or intermittent motion, an accelerated motion 55 of rotation, and having a cone-shaped orifice of less diameter than said path of rotation freely opening into said chamber, said orifice adapted to discharge said gases from said chamber in an unobstructed expanding and 60 rotating stream, and said chamber having foraminous lined passages, substantially as described.

9. In an apparatus for muffling sounds the combination of a casing provided with 65 receiving and discharge chambers, and with an inlet and an outlet respectively for said chambers; a helically disposed member pro- 70 vided with a wire cloth covering, located in said casing between said chambers and cut away near its outlet end to provide an unobstructed passage to said discharge chamber, substantially as described.

In testimony whereof I affix my signature.

JOSEPH O. FISHER.
